WALL AND CEILING COVERING.

No. 19,622.

Patented Jan. 28, 1890.

UNITED STATES PATENT OFFICE.

PAUL GROEBER, OF RUTHERFORD PARK, NEW JERSEY, ASSIGNEE TO
FREDERICK BECK, OF NEW YORK, N. Y.

DESIGN FOR A WALL AND CEILING COVERING.

SPECIFICATION forming part of Design No. 19,622, dated January 28, 1890.

Application filed December 26, 1889. Serial No. 335,053. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

5 The leading feature of my design consists of vases 1, having scrolls at bases with volutes and rosettes 2 and 3. Two rosettes 4 and 5 support a festoon 6 of leaves bound with bands, over which is a wreath of leaves

and fruit 7, with ribbon at base. There is 15 a beaded upper border and a lower border divided in panels, some of which are beaded.

What I claim is—

The design for a wall and ceiling covering herein shown and described, consisting of 20 vases with scroll-base, festoons, wreaths, and ribbons, with a beaded upper and lower border.

PAUL GROEBER.
